UNITED STATES PATENT OFFICE.

JAMES P. ATHERTON AND CHARLES E. RICE, OF LIVERMORE, KENTUCKY.

TOBACCO-HILLER.

No. 869,126.

Specification of Letters Patent.

Patented Oct. 22, 1907.

Application filed August 8, 1907. Serial No. 387,717.

To all whom it may concern:

Be it known that we, JAMES P. ATHERTON and CHARLES E. RICE, citizens of the United States, resident of Livermore, in the county of McLean and State 5 of Kentucky, have made a certain new and useful Invention in Tobacco-Hillers; and we declare the following to be a full, clear, and exact description of the same, such as will enable others skilled in the art to which it appertains to make and use the invention, reference 10 being had to the accompanying drawings, and to letters or figures of reference marked thereon, which form a part of this specification.

Figure 1 is a side view of the invention partly broken away. Fig. 2 is a plan view of the invention. Fig. 3 15 is a detail view of one of the scraper blades and its carrying arms.

The invention has relation to improvements in tobacco hillers to form the hills or ridges and pack the dirt in the same, and it consists in the novel construction and combinations of parts as hereinafter set forth.

In the accompanying drawings, illustrating the invention, the letters *a*, *a'*, designate the parallel supporting frame bars at each side of the machine. *b*, is a guide wheel at the front of the machine having its axle 20 *b'*, extended horizontally at each side and provided with journal bearings *y* in the frame bars *a*, *a'*. *c*, is a roller or packing wheel at the rear, of similar diameter to that of the wheel *b*, and having its axle *c'*, also extended horizontally at each side and provided with journal 25 bearings *w* in the bars *a*, *a'*. The frame bars are thus connected and braced at front and rear by the axles of the wheels *b*, and *c*, and as the wheels have similar diameters the frame bars are horizontal.

Intermediately of the wheels *b*, and *c*, are hinged to 30 the frame bars at each side two downward and rearward extending arms *d*, *d'*, carrying at their lower ends the scraper blades *e*, *e'*, which have a converging relation to each other to gather the dirt into a hill or ridge. The scraper blade carrying arms *d*, *d'*, are connected together

by a brace rod *f*, and are provided each with a lever adjustment device *g*, fulcrumed to the frame bars *a*, *a'*, at *g'*, and having link connections *g''*, with the arms, whereby such arms and the scraper blades carried thereby may be adjusted to any height desired. In order that the scraper blades may be at the same time 45 adjusted to the proper angle with relation to the ground, the arms *d*, *d'*, have arcuate slots *d'*, at their lower end portions through which pass the attachment bolts *d''*, for such blades. In practice the packing wheel or roll at the rear is made a little smaller than the front or 50 guide wheel, in order that it may ride upon the ridge or hill.

A draft link *h*, is connected to the frame bars at the front and extends forward at each side and in front of the guide wheel.

Having described the invention, what I claim and desire to secure by Letters Patent is:

1. A tobacco hiller including a front guide wheel, a rear packing wheel having a broad tread, a frame bar at each side carried upon the axles of such wheels, downward and rearward extending arms hinged to such frame bars and carrying at their lower end portions converging scraper blades located between the front and rear wheels, means for adjusting the height of said arms, and means for adjusting the angle of the scraper blades with relation to 60 the ground.

2. A tobacco hiller including a front guide wheel, a rear packing wheel of similar diameter having a broad tread, a frame bar at each side carried upon the axles of such wheels, downward and rearward extending arms hinged to the frame bars and provided with arcuate slots at their lower end portions, adjustable scraper blades having attachment bolts engaging such slots, and a lever device for 70 adjusting such arms and having link connection therewith hinged to one of said frame bars.

In testimony whereof we affix our signatures, in presence of two witnesses.

JAS. P. ATHERTON.
CHARLES E. RICE.
